ABSTRACT: A system including a module for providing an audible or visual and electrical signal in response to a changed condition. The electrical signal is fed to a second module which provides a reversed polarity output on receipt of the signal. The reversed polarity output is coupled to a third remote module which provides a plurality of indications including an indication of normal conditions and alarm conditions. A fourth module provides power for the system and an auxiliary alarm indication.

FIG. 1

MODULAR ALARM SIGNALING SYSTEM

BACKGROUND OF THE INVENTION

Alarm-signaling systems are about as old as man himself, and through the years, they have been improved as man's technology improved. The greater portion of alarm systems sold at the present time are electromechanical systems which include mechanical moving parts operated by relays. These systems lack reliability because the mechanical parts get dirty and wear out. In addition, such systems require considerable expensive battery power which requires constant replacement.

SUMMARY OF THE INVENTION

The present invention provides a relatively simple low power, all-electronic system which is versatile in its alarm responsiveness and which can be readily modularized as separately operable units. The system can provide both local and remote alarm indications. Since the system is modular, it can be added to at any time.

DESCRIPTION OF THE DRAWING

FIG. 1 is a schematic representation of two circuits which form a portion of the system of the invention; and

FIG. 2 is a schematic representation of two other circuit modules which combine with those of FIG. 1 in forming the system of the invention.

DESCRIPTION OF THE PREFERRED EMBODIMENT

The system shown and described includes various semiconductor devices including diodes, transistors, and other switching devices. These devices are shown schematically in the form usually employed by the industry.

The system of the invention 10 comprises a first alarm condition sensing module 20 which includes a DC power source 30 connected between buses 40 and 50. The module 20 has an alarm indicator including a three-electrode semiconductor gate or switching device 60 known as an SCR connected in series with load resistor 70 between buses 40 and 50 with an alarm bell or horn or the like represented by block 80 connected across resistor 70. The gate of SCR 60 is connected through a resistor 82 to bus 50 and to negative potential. SCR 60 is normally held off by the applied potentials. The anode of SCR 60 is also coupled through diode 90 and lead 100 to a second module 110, a polarity-reversing circuit, to be described.

A first alarm-sensing arrangement in module 20 includes a semiconductor switch 120, preferably a G.E. 4987 unilateral switch, having its anode A connected through a resistor 130 to the bus 40 and to positive potential, and its gate G connected through a normally closed switch 140 and through a second DC power source 150 to the bus 50. The cathode K of switch 120 is connected to a lead 160 which is connected to resistor 82 and thus to negative reference potential or ground. Power sources 30 and 150 normally hold switch 120 nonconducting, and switch 140 represents a mechanical or electronic sensor switch or any other sensing mechanism which, when opened, upsets the bias arrangement and permits switch 120 to conduct current from anode to cathode and to the gate of SCR 60 which also then conducts, energizes alarm 80, and provides an output current on lead 100 from diode 90. Device 140 may be a fire alarm or the like, or it may be several alarm-sensing devices connected in parallel.

A second similar alarm-sensing arrangement in module 20 includes a normally open switch 170 which, like switch 140, represents an alarm sensor connected in series with a resistor 180 between buses 40 and 50. Again, a plurality of similar alarm sensors might be connected in parallel. This sensing arrangement also includes a second similar unilateral switch 190 having its anode connected through a resistor 200 to bus 40 and its gate connected to the lead 210 between resistor 200

and switch 170. The cathode electrode of switch 190 is connected through a variable resistor 220 and capacitor 230 to bus 50 and through a second resistor 240 to the anode A of a unijunction transistor 250. The junction 260 of the variable resistor 220 and the capacitor 230 is connected to the trigger T of the unijunction transistor 250, and the cathode K of the unijunction transistor is connected to the gate of the SCR 60. Resistor 220 and capacitor 230 comprise an adjustable timing circuit for controlling the charging time of capacitor 230 and the turn-on time of unijunction 250. This time-delay mechanism permits an authorized entrant to trip sensor 170 and then reset it before alarm 80 is set off.

Sensors 140 and 170 are shown as normally closed and normally open, respectively, to indicate that module 20 can accommodate alarm sensors of different types in its two sensing circuit loops.

In the polarity-reversing module 110, the lead 100 from module 20 is connected to the gate G of a unilateral switch 260, the anode A of which is connected through a resistor 270 to bus 40. Switch 260 is normally held nonconductive. The gate G is also connected through a resistor 280 to the bus 40. The cathode K of the switch 260 is connected to the base of an NPN transistor 290, the emitter of which is connected to the bus 50 by lead 292, and the collector of which is connected to the base of a PNP transistor 300. The PNP transistor 300 has its collector connected to the lead 292 and its emitter connected by lead 310 to the base electrodes of two PNP transistors 320 and 330. The emitter of the transistor 320 is connected to an output terminal 340 and through a load resistor 350 to the positive terminal of a DC power source 370, the negative terminal of which is connected to the bus 50. The transistor 320 also has its collector electrode connected to the bus 50. The transistor 330 has its emitter electrode connected to the lead 360, and its collector electrode connected both to an output terminal 380 and through a load resistor 390 the bus 50.

Module 110 operates as follows. With module 20 quiescent and no alarm condition present, no signal is conducted through diode 90 to module 110, and this module is quiescent. In the quiescent state of module 110, switch 260 and all transistors are nonconducting and terminal 340 carries positive potential and terminal 380 carries negative potential. When an alarm condition in module 20 provides current flow on lead 100, switch 260 conducts and transistors 290 and 300 turn on, and this causes transistors 320 and 330 to turn on. Now, the emitter of transistor 320 assumes a negative potential, as does terminal 340, and the collector of transistor 330 assumes a positive potential, as does terminal 380. Thus, it can be seen that the normal polarity of terminals 340 and 380 are reversed during an alarm-indicating condition of the system.

Lines 400 and 410 are input leads to module 420 and are coupled to terminals 340 and 380 at the output of module 110. Lines 400 and 410 represent telephone lines or the like to a remote location, for example, a police station, firehouse, or the like, at which module 420 may be remotely located.

Line 400 is coupled through a diode 422 oriented as shown to line 430. Line 410 is coupled through an oppositely oriented diode 440 as shown to line 450. Line 400 is also coupled through lead 460 and a diode 470 oriented oppositely to diode 422 to line 480, and line 410 is also connected through lead 490 to a diode 500 oriented oppositely to diode 440 to line 510. Lines 450 and 480 are connected together by a lead 520, and line 430 is coupled to the base electrodes of two NPN transistors 530 and 540. Line 510 is coupled to the base electrode of another NPN transistor 550.

The module 420 includes a first "trouble" light 560 in series with an SCR 570, a "normal" light 580 in series with an SCR 590, and an "alarm" light or signal 600 of any suitable type in series with an SCR 610. The three condition-indicating devices 560, 580, and 600 are connected in parallel, with the cathodes of the SCR's connected together by lead 620 and with the free terminal of each device connected together to lead 630 which is connected to one side of an AC power

source 640. The gate electrodes of the SCR's are also connected through resistors 650 to a common bus 660 which represents reference potential and is connected by lead 670 to the other side of power source 640.

The first-described portions of module 420 and the "alarm" or "normal" are interconnected as follows. The collector of transistor 530 is connected by lead 700 through resistor 710 to the gate of SCR 570 to "trouble" indicator 560 and through resistor 720 and lead 730 to bus 740. The emitters of transistors 530 are connected through resistors 750 to lead 450 which is connected to reference bus 660. The emitter of transistor 540 is connected by lead 760 and resistor 770 to the gate of SCR 590 to the "normal" indicator 580, and the collector of transistor 540 is connected through resistor 780 to bus 730 to the power supply.

Line 400 is connected through lead 460, diode 422, lead 480, resistor 790, lead 800 and resistor 810 to the gate of SCR 610 of "alarm" indicator 600. The emitter of transistor 550 is connected to lead 800 to SCR 610, and its collector is connected through resistor 820 and lead 740 to the power supply.

A pulse-generating circuit in module 420 includes connections from lead 510 to the base of transistor 550 through a resistor 830, lead 834, and capacitor 840 to bus 660. Lead 510 is also connected by lead 850 to the anode of SCR 860 which has its cathode connected through a resistor 870 to bus 660 and through a capacitor 880 and lead 890 to a remote alarm to be described. The gate of SCR 860 is connected to lead 834 and through a resistor 900 to bus 660.

The power supply for the system 10 includes the usual 110 volt, 60 cycle AC power source 900 coupled to a transformer having primary and secondary windings 910 and 920, respectively. The secondary winding of the transformer has one end 903 connected through a lead 940 to lead 630 which is connected to one side of each of the signal devices 560, 580, and 600. This connection provides alternating current across these devices between bus 630 and bus 660. This end of the secondary winding of the transformer is also connected through a diode 950 and lead 960 to the lead 740 to provide half-wave rectified DC on lead 740 and thus to lead 730. The other end 980 of the secondary winding of the transformer is connected by lead 970 and lead 670 to the reference bus 660. A capacitor 990 is connected between leads 960 and 970. This capacitor acts as a filter and phase shifter.

An auxiliary alarm circuit is also provided including an SCR 1000 having its cathode connected to the lead or bus 970 and its anode connected through a load resistor 1010, a lead, and a switch 1020 to the lead 960. A suitable alarm 1030 is connected across the load resistor 1010. The gate of the SCR 1000 is connected through a resistor to the reference bus 970 and to lead 890 to capacitor 880.

Referring to circuit module 420, as mentioned, when the system is normal, that is, no alarm condition exists in module 20, line 400 is plus and line 410 is minus. With line 400 plus, positive voltage is coupled through diode 422 to turn on both NPN transistors 530 and 540. With transistor 530 turned on, its collector is at ground potential so that the signal voltage which is applied to bus 740 from the power supply is fed to ground and SCR 570 is not turned on and "trouble" light 560 is not turned on. With NPN transistor 530 on, a path is provided through the emitter-collector path of transistor 530 for the signal on bus 740, and this is applied to the gate of SCR 590 which opens SCR 590 and turns on the "normal" light 580.

If potential is removed from lines 400 and 410 for any reason, either due to opening of a line or shorting of the lines, then the transistors 530 and 540 remain off and "trouble" light 560 is turned on by the signal voltage on lines 740 and 730 passing through resistors 720 and 710 to the gate of SCR 570 which is rendered conductive.

When the potentials on lines 400 and 410 are reversed indicating an alarm condition, diodes 422 and 440 are blocked, transistors 530 and 540 are off and signal voltage is coupled from the power supply through lines 740 and 730 through re-

sistor 720 to the gate of SCR 570 which conducts and "trouble" light 560 goes on. Also, diodes 470 and 500 open, and the positive potential on line 410 now operates through diode 500, to turn on transistor 550. The emitter-collector path of transistor 550 passes signal voltage on line 740 through lead 800 and resistor 810 to the gate of SCR 610, which thereby conducts and turns on the alarm 600.

In addition, plus voltage applied to diode 500 is applied to the anode of SCR 860, and current flow through resistor 830 charges capacitor 840 which, when charged, acts on the gate of SCR 860 to turn on SCR 860 and send a pulse through capacitor 880 to turn on remote SCR 1000 and thus activate remote alarm 1030 shown in the power supply circuit. This arrangement using capacitor 840 prevents spurious noise pulses from turning on SCR 860 since such pulses are fed to ground through resistor 900 and do not charge the capacitor. Switch 1020 can be used to deactivate or turn off alarm 1030, if this is desired, without affecting the other alarms in the system.

What is claimed is:

1. An alarm sensing and indicating system including first alarm signalling means, a first electronic circuit module including first bistable switching means having two states of operation, in one of which it is unenergized and quiescent and, in the second of which, it senses a first alarm condition and generates a first electrical signal in response thereto, said first electrical signal operating said first alarm signalling means, a second electronic circuit module including second bistable switching means having two states of operation, in one of which it is unenergized and quiescent and, in the second of which, it senses a second alarm condition and generates a second electrical signal in response thereto, said second electrical signal operating said first alarm signalling means, a third electronic circuit module coupled to said first and second electronic circuit modules and having input terminals coupled thereto and also having first and second output terminals coupled to second signalling means for indicating which of its two states each of said first and second electronic circuit modules is in, said output terminals of said third electronic circuit module carrying one set of potentials and energizing one portion of said second signalling means when said first and second circuit modules are in an unenergized and quiescent state, said output terminals carrying a second set of potentials and energizing another portion of said second signalling means when one or both of said first and second electronic circuit modules is in an alarm-signalling state.
2. The system defined in claim 1 wherein one of said first or second circuit modules includes time delay means for delaying its operation of said first alarm signalling means.
3. The system defined in claim 1 and including a fourth circuit module coupled to said third module and including first signalling means indicating a normal state for said system when said output signal is not present and said third module is in said first state, and second signalling means indicating an alarm state when said output signal is present and said third module is in said second state.
4. The system defined in claim 3 wherein said fourth module includes first circuit means including an alarm condition indicator and a gate, and second circuit means including a normal condition indicator and a gate, first power supply means coupled to and applying an AC signal across both said alarm condition indicator and gate, and said normal condition indicator and gate, each said gate preventing said AC signal from turning on either indicator, and a second power supply means coupled through control means to said gates for applying an enabling signal thereto and for operating the same and their associated indicators under control of said control means.
5. The system defined in claim 1 and including

a fourth circuit module coupled to said third circuit module wherein said first and second output terminals of said third circuit module are coupled through a first pair of oppositely oriented diodes to a pair of switching devices, one of said switching devices being coupled through a first circuit path to a first indicator representing "trouble" and through a second circuit path to a second indicator representing "normal," 5
 said first and second output terminals also being connected through a second pair of oppositely connected diodes to third and fourth circuit paths, said third circuit path including a circuit connection including a switching device to a third indicator representing "trouble" and said fourth circuit path including a fourth remote "trouble" indicator, and 10
 a signal source providing signals for operating said first, second, and third indicators and coupled to said first, second, and third circuit paths, said paths being open or blocked to said signals depending on the conductive state of said first and second pairs of devices, and the state of 15
 said diodes being determined by the potentials on said first and second output terminals of said third circuit module.
 6. The system defined in claim 5 wherein said fourth circuit path includes a pulse generating circuit which comprises a switch and a capacitor, said switch being rendered conductive to operate said fourth "trouble" indicator when said capacitor is charged by current flowing in said fourth circuit path as the 20 result of an alarm condition sensed by said system.
 7. The system defined in claim 1 and including 25
 a fourth circuit module coupled to said third circuit module wherein said first and second output terminals of said third circuit module are coupled through a first pair of oppositely oriented diodes to first and second switching devices which are connected so that they turn ON and 30
 OFF together in response to the potentials on said first 35

and second output terminals of said third module, said first switching device being coupled through a first circuit path to a first "trouble" indicator having a first gate and through a second circuit path to a second "normal" indicator having a second gate,
 said first and second output terminals also being connected through a second pair of oppositely connected diodes to third and fourth circuit paths, said third path including a circuit connection including a switching device to a third "trouble" indicator having a third gate, said fourth path being coupled to a fourth remote "trouble" indicator having a fourth gate, and
 a signal source providing signals for operating said first, second, and third indicators and coupled to said first, second, and third circuit paths, said paths being open or blocked to said signals depending on the conductive state of said first and second pairs of devices, and the state of said diodes being determined by the potentials on said first and second output terminals of said third circuit module.

8. The system defined in claim 7

wherein said first and second switching devices comprise first and second semiconductor devices coupled together and adapted to be ON or OFF together in response to signals on said first and second output terminals of said third module,
 when said devices are ON together, they are in condition to couple signals from said signal source to said second gate to operate said second "normal" indicator and at the same time they are connected to prevent said signals from energizing said first gate and said first "trouble" indicator, when said devices are OFF together, said third and fourth circuit paths are operative and operate their indicators.
